Samuel W. Gibbs (a perf. of J. C. Polley) Albany N.Y.
Letters Patent (Design No. 158) dated 23 Oct. 1847.

The schedule referred to in these Letters Patent and making part of the same.

To all whom it may concern: Be it known that I, Samuel W. Gibbs of Albany in the County of Albany and State of New York, have invented and produced a new ornamental design, for an Airtight Parlor Stone, and I do hereby declare that the accompanying drawing is a full and accurate delineation of a stone after my said design, the sides not seen in the drawing being exactly similar to those represented.

What I claim as my invention and desire to secure by letters patent is, the combination and arrangement of ornamental forms and figures exhibited in the accompanying drawing, and forming an ornamental design for an airtight Parlor Stone.
